UNITED STATES PATENT OFFICE.

WILLIAM SCHRANK, OF PHILADELPHIA, PENNSYLVANIA.

NOZZLE.

1,251,118.

Specification of Letters Patent. Patented Dec. 25, 1917.

Application filed June 15, 1914. Serial No. 845,172.

To all whom it may concern:

Be it known that I, WILLIAM SCHRANK, a citizen of the United States, residing at Philadelphia, in the county of Philadelphia and State of Pennsylvania, have invented 5 certain new and useful Improvements in Nozzles, of which the following is a specification.

This invention relates to improvements in 10 nozzles and has for its object to provide a combined water spray, jet, and sprinkler.

Another object of the invention is to provide a fire hose nozzle having means for producing a water shield.

15 Still another object of the invention is to provide a fire hose nozzle having a sprinkler in combination therewith.

With the above and other objects in view, I have invented the device illustrated in the 20 accompanying drawings in which—

Figure 1, is a longitudinal, sectional view of my improved nozzle.

Fig. 2, is a detail plan view of a closure member.

25 Fig. 3, is a section on line A—A of Fig. 1.

Fig. 4, is a top plan view of Fig. 1, with a collar removed.

Fig. 5, is a view similar to Fig. 1, of a modified form of the device.

30 Fig. 6, is a section on line A—A of Fig. 4.

Fig. 7, is a detail plan view of a valve member,

Fig. 8, is a section on line B—B of Fig. 5 and Fig. 1.

35 Like reference characters designate like or corresponding parts throughout the different views in which 1, indicates a nozzle consisting of a valve chamber 2, having an inlet 3, and an outlet 4, which are internally 40 screw-threaded, the latter to receive the screw threaded bell-shaped spray member 5. At its inner end, the member 5, is provided with a series of screw-threaded lugs 6, to which the similar shaped but smaller

45 spreader member 7, is screwed. The member 7, is provided with a series of passages 8, and a larger central passage 9, the projecting wall portion 10, being screw-threaded at its extreme end to receive the nozzle 11. A collar 12, is adapted to seat revolvably on the portion 10, and is provided with a series of peripheral projections 13, which are equal in number to the openings 8, and which in one position of said collar 12, are adapted to 50 form closures for the said openings 8.

The chamber 2, is cylindrical and has

seated therein a rotatable valve member 14, which is hollow and has an outer wall 15, with an opening 16, adapted to align with the opening 9, and another opening 17, of a 60 length to align with the inlet 3, when the valve is in any one of several positions. The opening 16, is large enough in diameter to admit liquid into the openings 8, as well as the opening 9. A series of openings 18, in 65 the wall 15, are adapted to align with the outlet 19, between the members 5 and 7, and the portion 20, of the wall 15, is adapted to close the outlets 8 and 9, when the openings, 18, align with the outlet 19. The wall portion 21, is adapted to form a closure for all of the outlets 8, 9 and 19, and together with the wall portions 22, is adapted to close the outlet 19, when the opening 16, aligns with the openings 8 and 9. When the opening 75 16, is brought adjacent and in alinement with the opening 9, the opening 17, permits the passage of liquid from the chamber 23, to all of the openings 8, 9, and 19. A lever 24, is fixed to the boss 25, on the exposed side wall 26, of the member 14, whereby said valve may be operated. The member 14 is also provided with a screw portion 27, which projects through the opening 28, in the wall 29, in the chamber 2, to receive the nut 30, whereby said valve member 14, is held in place. The collar 12, has a slot 31, through which projects the screw 32, whereby said collar is held rotatably in place.

90 From the above description it will be readily seen that a single stream of liquid may be forced through only the outlet 9, or through only the outlets 8, where a spray is provided, or through the outlet 19, in which case a continuous thin wall of liquid is had which will either form a shield of water for a fireman, to protect him from the heat of a flame or act as a sprinkler of a large surface, or water may be passed through any desired combination of the outlets.

95 In Figs. 5 and 6, I show a modification of the invention in which the spraying nozzle 33, is formed of a single piece, the members 34 and 35, being held together by integrally connecting webs 36, between which are openings 37. There is only one central outlet 38, in the member 35.

100 Having thus described my invention what I claim as new and desire to secure by Letters Patent is:

105 1. The described device consisting of a nozzle formed of a pair of bell shaped mem-

- bers one within the other, said members being spaced apart to form a flaring passage, said inner member having a plurality of passages, a tubular extension on said inner member and means on said extension for closing said plurality of passages. 5
2. The described device consisting of a nozzle formed of a pair of bell shaped members one within the other, said members being spaced apart to form a flaring passage, and screw threaded ribs on the inner surface of said outer member, said inner member being screw threaded whereby said members are held together. 10
- 15 3. A nozzle having an outer tube and an inner tube screwed thereto, said inner tube having a central channel and a series of smaller channels spaced therearound, said tubes being separable from one another, the 20 walls of said central channel projecting beyond the walls of said smaller channels, a collar rotatable on said projection having means for closing said smaller channels, said means consisting of longitudinal ribs.
- 25 4. A nozzle having an outer tube and an inner tube screwed thereto, said inner tube having a central channel and a series of smaller channels spaced therearound, said tubes being separable from one another, the 30 walls of said central channel projecting beyond the walls of said smaller channels, a collar rotatable on said projection having means for closing said smaller channels, said means consisting of longitudinal ribs, said 35 nozzle having a cylindrical enlargement and a cylindrical valve member rotatable therein.
5. A nozzle having an outer tube and an inner tube screwed thereto, said inner tube having a central channel and a series of 40 smaller channels spaced therearound, said tubes being separable from one another, the walls of said central channel projecting beyond the walls of said smaller channels, a collar rotatable on said projection having 45 means for closing said smaller channels, said means consisting of longitudinal ribs, said nozzle having a cylindrical enlargement and a cylindrical valve member rotatable therein, said member having a plurality of openings 50 therethrough.
6. A nozzle having an outer tube and an inner tube screwed thereto, said inner tube having a central channel and a series of smaller channels spaced therearound, said 55 tubes being separable from one another, the walls of said central channel projecting beyond the walls of said smaller channels, a collar rotatable on said projection having

means for closing said smaller channels, said means consisting of longitudinal ribs, said 60 nozzle having a cylindrical enlargement and a cylindrical valve member rotatable therein, said member having a plurality of openings therethrough, and means for closing one or more of the passages through said tubes. 65

7. A nozzle having an outer tube and an inner tube screwed thereto, said inner tube having a central channel and a series of smaller channels spaced therearound, said tubes being separable from one another, the 70 walls of said central channel projecting beyond the walls of said smaller channels, a collar rotatable on said projection having means for closing said smaller channels, said means consisting of longitudinal ribs, said 75 nozzle having a cylindrical enlargement and a cylindrical valve member rotatable therein, said member having a plurality of openings therethrough and means for closing one or more of the passages through said tubes, 80 said outer tube being flared, the outer wall of said inner tube being flared, said outer tube having internal screw threaded ribs to which said inner tube screws.

8. The described device consisting of a 85 nozzle formed of a pair of bell shaped members one within the other, said inner member having a tubular extension, said members being spaced apart to form a flaring passage, said inner member having a central 90 passage connected with the tubular extension and a plurality of smaller passages around said central passage, a rotatable collar on said extension having means for closing said smaller passages. 95

9. The described device embracing a valve member and a nozzle, said nozzle consisting of a pair of bell shaped members, one within the other, said inner member having a tubular extension, said members being spaced 100 apart to form a flaring passage, said inner member having a central passage connected with the tubular extension and a plurality of smaller passages around said central passage, a rotatable collar on said extension 105 having means for closing said smaller passages, said means consisting of a plurality of longitudinal ribs, said valve member having ports adapted to align with one, certain of, or all of said passages. 110

In testimony whereof I affix my signature in presence of two witnesses.

WILLIAM SCHRANK.
